Atlys.

UNITED STATES PATENT OFFICE.

RICHARD SMITH, OF YUMA, ARIZONA.

TRAFFIC SIGNAL.

Application filed April 1, 1925. Serial No. 19,850.

To all whom it may concern:

Be it known that I, RICHARD SMITH, a citizen of the United States, residing at Yuma, in the county of Yuma and State 5 of Arizona, have invented new and useful Improvements in Traffic Signals, of which the following is a specification.

An object is to make an improved traffic signal, mount one of the signals upon each 10 side of a motor vehicle and operate the signals from the steering wheel.

Another object is to make an improved traffic signal adapted to be mounted upon a motor vehicle and to show the signal indications forwardly, backwardly and outwardly.

Other objects and advantages will appear from the drawing and specification. The invention consists of the novel features 20 herein shown, described and claimed. The drawings illustrate the invention.

Figure 1 is a fragmentary rear view showing a steering wheel and wind shield of a motor vehicle with my improved traffic signals mounted upon the sides of the wind 25 shield.

Fig. 2 is a top plan view of one of the traffic signals as seen looking in the direction indicated by the arrow 2 in Figs. 1, 3 30 and 4, parts being broken away and shown in section, and the signal being detached from the wind shield frame.

Fig. 3 is a vertical sectional elevation on the line 3—3 of Fig. 2 and on a plane parallel with Figs. 1 and 4.

Fig. 4 is a rear elevation upon an enlarged scale looking in the same direction as Fig. 1 and in the direction indicated by the arrow 4 in Fig. 2.

Fig. 5 is a cross section on the lines 5—5 of Figs. 2 and 3.

Fig. 6 is an electrical diagram showing how the lamps in the signals are connected to the electric system of the motor vehicle 45 and controlled by switches mounted on the steering wheel.

The details of construction and operation are as follows:

The traffic signals 1 and 2 are substantially alike, the signal 1 being mounted upon the left hand wind shield post 3 and the signal 2 being mounted upon the right hand wind shield post 4. The clamping plate 5 is concavo-convex and adapted to fit one 55 side of the post 3 and the clamping plate 6

is concavo-convex and adapted to fit the other side of the post 3. A rigid supporting arm 7 extends from the clamping plate 5 and is channel shaped in cross section as shown in Fig. 5. The loose arm 8 extends from the clamping plate 6 and is channel shaped in cross section, the channel of the arm 8 fitting within a channel of the arm 7 to hold the clamping plates 5 and 6 in alinement. The clamping plates 5 and 6 60 extend some distance up and down and are connected by wing nut screws 9 and 10, the screws being between the clamping plates 5 and 6 and the channels of the arms 7 and 8 so that when the screws are tightened the channels will be drawn together 65 and then the plates 5 and 6 will be drawn together to grip the post 3.

Attaching flanges 11 and 12 extend upwardly and downwardly from the outer end of the supporting arm 7 and the back plate 13 is secured to the flanges 11 and 12 by rivets 14. The back plate 13 is rectangular in elevation and forms the inner side 70 of the signal. The upper head 14 is formed integral with the upper end of the back plate 13 and the lower head 15 is formed integral with the lower end of the back plate 13, the heads 14 and 15 being substantially 75 square in plan.

Ring flanges 16 and 17 are stamped and drawn from the centers of the heads 14 and 15 and extend downwardly and upwardly respectively. Lamp sockets 18 and 19 are mounted in the flanges 16 and 17 and lamps 80 20 and 21 are mounted in the sockets. Preferably one point lamps are used and are grounded by not being insulated upon the frame work. Spring contacts 22 and 23 are mounted upon the screws 24 and 25, inserted through the heads 14 and 15 and insulated therefrom, and the free ends of the contacts 22 and 23 engage the points of the lamps 20 and 21. Wires 26 and 27 are attached to the screws 24 and 25 and lead 85 through openings in the back plate 13 and through the space 28 between the channels 7 and 8 and then downwardly along the post 3.

A partition 29 is mounted halfway between the heads 14 and 15 and fixed to the back plate 13 to form a division between the light chamber 30 and the light chamber 31. The posts 32 and 33 are inserted 90 between the heads 14 and 15 and secured to 95 the back plate 13.

the back plate 13. Posts 34 and 35 are inserted between the heads 14 and 15. Corner portions 36 of the heads 14 and 15 fit against the ends of the posts 34 and 35 at 5 the inner corners of the posts as shown in Fig. 2. A flange 37 extends downwardly from the forward edge of the head 14 and fits between the posts 32 and 34. A similar flange 38 extends downwardly from the 10 outer side of the head 14 and fits between the posts 34 and 35, and a third flange 39 extends downwardly from the rear edge of the head 14 and fits between the posts 33 and 35 and the ends of the flanges 37, 38 and 15 39 are welded or brazed to the post. The head 15 is connected to the lower ends of the posts 32, 33, 34 and 35 in the same manner as the head 14, so as to make a 20 substantial frame, square in plan and rectangular in elevation. The posts 32 and 34 are grooved upon the confronting faces immediately outside of the flange 37 and the glass plate 40 slides downwardly into these grooves. In a like manner the confronting faces of the posts 34 and 35 are 25 grooved and the outer glass plate 41 slides downwardly into these grooves and the confronting faces of posts 33 and 35 are grooved and the rear glass plate 42 slides 30 downwardly into these grooves.

The top cover 43 has a flange 44 fitting around the posts 32, 33, 34 and 35 and extending along the back plate 13 and the upper edges of the glass plates 40, 41 and 42, 35 and the cover is held in place by screws 45 and 46 inserted through the back part of the flange and tapped into the posts 32 and 33, so that by removing the screws 45 and 40 46 the cover 43 may be removed and the plates 40, 41 and 42 removed if desired to provide access to the lamps 20 and 21 and the other parts within the frame, or to renew the glass. The lower cover plate 47 is substantially like the upper cover 43 and 45 has shoulders 48 to support the plates 40, 41 and 42, and the cover 47 is held in place by cap screws 49 similar to the screws 45 and 46.

The upper halves of the plates 40, 41 and 50 42 are colored red and marked "Right" in black letters, and the lower edges of these plates are colored blue and marked "Left" in black letters so that in daylight the black letters will show without illuminating the 55 lamps 20 and 21 and so that at night if the lamp 20 is illuminated the light chamber 30 will be illuminated to show a red background around the black "Right" letters, and if the lamp 21 is illuminated the light 60 chamber 31 will be illuminated to show a blue background around the black "Left" letters, the partition 29 serving to separate the two light chambers.

As before suggested, the signal 2 is constructed and mounted in the same manner as 65 the signal 1 already described.

Referring to the diagram shown in Fig. 6, the wires 26 are brought to and attached to a common wire 50 and this wire 50 leads to a right hand switch 51 mounted upon 70 the steering wheel 52. In a like manner the wires 27 are brought to and connected to a common wire 50 leading to a left hand switch 53 upon the steering wheel. Switches 51 and 53 are connected as a branch to the main line 54 of the motor vehicle electric system, the main line 54 leading to an ammeter 55, a battery 56 to a ground 57 which is the frame of the motor vehicle.

In the practical operation the operator of 80 the motor vehicle manipulating the steering wheel 52 will operate the switch 51 to give the right signal or he will operate the switch 53 to give the left signal.

The object in using the contrasting colors 85 red and blue is to attract attention to the lettering and to distinguish the right signal from the left signal even at a distance where the lettering could not be distinguished.

Various changes may be made without departing from the spirit of my invention as claimed.

I claim:

1. A traffic signal comprising a back plate, upper and lower heads extending from the back plate, posts mounted upon the upper and lower heads and formed with vertical confronting slideways, glass plates mounted in the slideways, an upper and a lower cover on the upper and lower heads, means removably securing said covers on the heads, a partition halfway between the upper and lower heads, means securing the partition between said heads and lamps secured in the upper and lower heads.

2. A traffic signal comprising a back plate, upper and lower heads extending from the back plate, posts mounted between the upper and lower heads and formed with vertical confronting slideways, glass plates mounted in the slideways, an upper and a lower cover on the upper and lower heads, means removably securing said covers to the said heads, a partition halfway between the upper and lower heads, means securing said partition between said heads, glass plates being colored red above the partition and blue below the partition and the words "Right" appearing above the partition and "Left" below the partition, and lamps secured to the heads on the inside thereof.

In testimony whereof I have signed my name to this specification.

RICHARD SMITH.
